US00D617063S

(12) **United States Design Patent**
Bischoff et al.

(10) **Patent No.:** **US D617,063 S**
(45) **Date of Patent:** **** Jun. 1, 2010**

(54) **FABRIC REFRESHING DEVICE**

(75) Inventors: **Corey Michael Bischoff**, Cincinnati, OH (US); **Benjamin James Beck**, Boston, MA (US); **Christopher James Page**, Somerville, MA (US)

(73) Assignee: **The Procter & Gamble Company**, Cincinnati, OH (US)

(**) Term: **14 Years**

(21) Appl. No.: **29/308,384**

(22) Filed: **Jun. 13, 2008**

(51) **LOC (9) Cl.** **15-05**

(52) **U.S. Cl.** **D32/6**

(58) **Field of Classification Search** ..... D32/1, D32/5-6, 8-9, 10; 68/3 R, 5 C, 5 R, 6, 12.01, 68/212; 34/132, 234, 622, 87-88, 104, 523-524, 34/597; 219/553; 312/31

See application file for complete search history.

(57) **CLAIM**

The ornamental design for a fabric refreshing device, as shown and described.

DESCRIPTION

FIG. 1 is a perspective view of a first embodiment of a fabric refreshing device showing our new design;

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof.

FIG. 8 is a perspective view of a second embodiment thereof;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken line showing of environmental structure in FIGS. 1-14 is for illustrative purposes only and forms no part of the claimed design.
